INVENTOR

ATTORNEY

UNITED STATES PATENT OFFICE.

CHARLES L. LAWRENCE, OF NEW YORK, N. Y.

TOOL KIT.

Application filed January 24, 1925. Serial No. 4,410.

My invention relates particularly to kits for mechanics' tools, such as wrenches. Such tools come in assorted sizes and varieties, for instance, every automobile mechanic has 5 to have two sets of wrenches for convenience in the work which he does, one set of cap screw wrenches and another set of nut wrenches. In addition to such wrenches, a mechanic is also obliged to use miscellaneous screw-drivers, hammers, files, gauges, scales, and etc. To facilitate his work it is 10 very desirable that he be able to carry these about and that he be able to find or pick out the desired tool with the least trouble and 15 confusion.

I have accordingly provided a kit which consists of a tray having a centrally disposed series of graduated compartments for the sets of wrenches which may be readily 20 turned about for convenience in getting at the desired tool. This tray is provided with a carrying case and the two parts are so designed and arranged as to provide in the case room not only for the tray and the 25 wrenches, but additional space for other tools as well as for overalls and waste.

Fig. 1 is a longitudinal sectional view and side elevation of a kit embodying the improvements of my invention, showing the 30 cover of the case closed.

Fig. 2 is a transverse sectional view showing the cover open.

Fig. 3 is a plan view of the tray showing the handle broken away.

The body of the case 5 may be of any suitable construction, for instance, of sheet metal, and provided with a cover 6 which is preferably hinged along one edge. The body and cover may be provided with suitable locks, latches, or catches, such as 7, 40 for holding the cover in place. The bottom of the case may be provided with bosses 8 serving as feet or supporting elements. The case may also be provided with some suitable form of handle 9 for convenience in carrying it.

The tray 10 may also be formed of sheet metal and have bosses or feet 11 at the corners so as to make it easier to slide the tray along and turn it around on the floor or bench. The tray is also preferably provided with some suitable form of handle 12 for convenience in carrying the tray when it has been removed from the case.

The tray is provided with a series of graduated compartments formed, in this

case, by concentric cylindrical walls 13, 14 and 15. The central cylinder is subdivided into a series of graduated compartments by partitions 16, 17, and 18 of different depths. 60 The outer and inner cylindrical walls are spaced apart at intervals by partitions such as 19, 20, 21, 22, 23, and 24. These partitions are so designed and arranged as to provide compartments of graduated depth 65 so as to accommodate two complete graduated series of wrenches.

The handle may be vertically adjustable for convenience in carrying the tray, such vertical adjustment being permitted by 70 having the lower ends of the bail 25 turned inwardly into slots or grooves in the wall 14. The handle may be prevented from tipping over by spaced lugs such as 26.

In order to enable the mechanic to get 75 at the wrenches which are on the side of the carrier which is away from him, I have mounted the wrench carrier so that it may be readily rotated. For this purpose the carrier has an upper plate 27 which forms 80 the bottom of all the wrench compartments. Another plate 28, which is secured to the outer wall 13, rests on anti-friction bearings 29 in the bottom of the tray. The carrier is mounted so as to rotate about the 85 spindle 30, which is secured to the bottom of the tray by means of a nut 31.

To prevent the body of the tray from rotating when the carrier is picked up, I provide an intermediate plate 33, which is secured to the spindle 30 and therefore non-rotatable. This plate 33 is provided with one or more holes, such as 32, adapted to receive a projection 34 which extends upwardly from the bottom plate 28 so that 95 when the tray is picked up by the handle it will rise on the spindle 30 and the projection 34 will enter the recess 32, thus preventing the body of the tray from rotating with respect to the carrier. When the tray is set 100 down, the weight of the carrier causes it to slide down on the spindle 30 and retract the projection 34 from the recess 32, thus permitting the carrier to be rotated.

In the cover of the case I may provide 105 one or more drawers or slides 35 each held in place by plates 36 and provided with a handle 37. This drawer may, of course, be opened only when the cover is opened, as shown in Fig. 1. Such a drawer is convenient 110 for carrying spare parts and small tools and the like. It will be noted that the ar-

angement and proportion of the parts is such that the handle 12 fits between the faces of the two drawers in the cover when the cover is closed so as to prevent the 5 drawers from sliding back and forth.

It will also be noted that there is considerable space in the opposite ends of the tray 10 for the carrying of miscellaneous articles and that there is also considerable space in 10 the case above the tray 10 for the storage of overalls, waste, or other articles which it is desired to carry around in a kit.

The tray is preferably provided with a sleeve 38 which surrounds the carrier so as 15 to prevent dirt or small articles such as washers, keys, nuts, bolts, wires, etc., from getting underneath and preventing rotation of the carrier in the tray. The tray can be of any suitable material such as wood, fibre 20 or aluminum.

The case may be reinforced in any suitable manner as for instance by bands such as 39 and 40. These bands can be formed either by pressing the metal outwardly as at 25 39 or by separate strips 40.

I claim:

1. A tool kit comprising a case having a hinged cover with sliding drawers oppositely disposed in the cover and a tray 20 mounted in the case having a carrying handle projecting between the drawers and holding them in position when the cover is closed.

2. A mechanic's tool kit comprising a tray 25 having a centrally disposed wrench carrier provided with parallel central compartments and other compartments concentri-

cally located around said central compartments and graded in depth and width to hold a graded set of wrenches. 40

3. A tool kit comprising a tray, a wrench carrier rotatably supported therein, a handle for said carrier and tray, and means for preventing said tray rotating with respect to said carrier when said carrier is lifted. 45

4. A tool kit comprising a tray, a wrench carrier rotatably mounted therein, and means for automatically interlocking the carrier and tray when the carrier is lifted. 50

5. A tool kit tray having a rotatable carrier with a series of compartments of graded size for carrying a graded set of wrenches and a sleeve surrounding said carrier and extending to the bottom of the tray to keep 55 articles from working under the carrier. 55

6. A mechanic's tool carrier comprising a tray, a central wrench holder mounted in said tray and having a series of wrench-holding compartments of graded depth, a wall surrounding said compartments lower 60 than said compartments, spacing partitions between said compartments and said wall providing a series of wrench chambers of graded depth shallower than the central compartments. 65

7. A mechanic's tool carrier comprising a tray having a deep central compartment, parallel partitions dividing it into chambers, two lower surrounding walls, and fixed partitions of graded height between said 70 walls, forming wrench-receiving chambers of graded depths. 75

CHARLES L. LAWRENCE.
